WEATHER SHIELD FOR A WINDOW OPENING
OF AN AUTOMOBILE

Laurence B. Tipper, #305, 1780 Lawrence Ave.,
Toronto, Ontario, Canada

Filed Aug. 3, 1962, Ser. No. 71,175

Term of patent 7 years

(Cl. D14—6)

FIG. 1 is a perspective view of a weather shield for a window opening of an automobile showing my new design, and viewed from the outer side;

FIG. 2 is an elevational side view thereof as viewed from the outer side;

FIG. 3 is a bottom plan view of the weather shield;

FIG. 4 is a rear end view thereof;

FIG. 5 is a cross section taken on the line 5—5 of FIG. 2; and

FIG. 6 is a cross section taken on the line 6—6 of FIG. 2.

I claim:

The ornamental design of a weather shield for a window opening of an automobile, as shown.
